MUNTIN ASSEMBLY CLIP

Milo G. Hodson, South Bend, Ind., assignor to
 The Kawneer Company, Niles, Mich., a corpora-
 tion of Michigan

Application October 31, 1941, Serial No. 417,298

4 Claims. (Cl. 189—76)

The present invention relates to window constructions and especially to a novel clip construction for facilitating the assembly of the vertical and/or horizontal muntins of a window construction with the surrounding sash members or rails. The invention further comprehends a novel clip for securely attaching together the vertical and horizontal muntins incorporated in the window assembly.

Another object of the invention is the provision of a simplified, more effective and more economical method and manner of attachment of muntins to the encompassing or associated sash rails than the prior methods such as the morticed and tenoned joints with the projected end of the tenon peened over, or the welded joints, now in general use.

The invention further comprehends a novel method and manner of attaching muntins to the previously assembled surrounding sash rails as distinguished from the methods now in use wherein the sash rails and muntins are simultaneously assembled. This further permits assembly of the complete window unit at the factory save for the muntins, and permits the ready assembly of any desired muntin design or arrangement to meet the architectural style desired by the customer.

The novel invention further provides a muntin assembly of increased strength by attaching the vertical muntins to bisecting horizontal muntins, the latter extending in one piece from side rail to side rail, instead of the prior method of halving together the horizontal and vertical muntins.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangements of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a view in front elevation of a window assembly employing the novel clip construction.

Figure 2 is a fragmentary view in vertical cross

section taken in a plane represented by the line 2—2 of Figure 3.

Figure 3 is a fragmentary view in vertical cross section taken in a plane represented by the line 3—3 of Figure 2.

Figure 4 is a view in horizontal cross section taken in a plane represented by the line 4—4 of Figure 2.

Figure 5 is a fragmentary top plan view of a horizontal muntin.

Figure 6 is a fragmentary perspective view taken from above the muntin and showing the novel manner of assembling a horizontal muntin to a vertical sash rail.

Figure 7 is a view in perspective of one of the novel clips.

Figure 8 is a view in perspective of the assembly shown in Figure 6 but with the view taken from below the muntin.

Figure 9 is a fragmentary view in vertical cross section through the web of the vertical side rail, muntin and assembly clip shown in Figures 6 and 8 but taken as these members are being assembled.

Figure 10 is a fragmentary view in vertical cross section similar to Figure 9 but showing the manner of assembly of a vertical muntin with a continuous horizontal muntin.

Figure 11 is an enlarged view similar to Figure 9 but showing a subsequent step in the manner of assembly.

Referring more particularly to the drawings in which is disclosed an illustrative embodiment of the novel invention, a metal window A is shown as equipped with side rails 1 and 2, top rail 3 and bottom rail 4. Secured to these rails are vertical muntins 5 and 6 and a horizontal muntin 7, the latter being shown in the form of a continuous member. The present invention relates primarily to a novel means and manner of assembling the vertical and horizontal muntins to the sash rails.

The novel metal assembly clip 8 is provided with a pair of downwardly or outwardly extending 45 projections or prongs 9, and a pair of upwardly or inwardly spaced projections or legs 10 and 11. In order to assemble these clips, as for example to the side rail 1, the web 12 of this side rail is provided with spaced openings 13 for the reception of the projections 9 and the web 14 of the horizontal muntin 7 is notched at 15 for the reception of the leg 10, coped at 16 and 17 to fit the contour of the rail 1, and provided with an opening 18 for the reception of the leg 11. The leg 10 is so spaced with respect to the

projections or prongs 9, that after the latter's insertion in the openings 13 and the plane of the body of the clip is brought up to within approximately 10° of being parallel to the plane of the muntin, both the prongs 9 and the leg 10 will be in contact with the web 12 of the rail 1 to which the muntin 7 is to be attached. As the clip is forced more nearly parallel with this muntin, the prongs 9 and the leg 10 grip firmly, with a slight expansion of these prongs. For this purpose, these projections or prongs 9 are turned or bent inwardly slightly as shown in Figure 10.

One end of the muntin 7 is dropped on clip 8 previously inserted in rail 1 with the legs 10 and 11 entering notch 15 and opening 18, respectively. The clip is then brought up parallel to the muntin 7 and leg 11 is bent over but is not firmly set. The other end of the muntin 7 is then dropped over a similar clip in the side rail 2 and the sequence of steps as outlined above is carried out with respect to that clip. When both ends of the muntin 7 have been loosely secured in place as described above, the leg 11 will be firmly set as shown in Figures 2 and 6, and the leg 10 is then bent over and firmly set, the operation being repeated in connection with side rail 2.

The projections and legs on the clip and the opening 18 in the muntin 7 are so spaced that when the leg 11 is firmly set it will draw the muntin toward the side rail 1 and firmly anchor and retain it in place. The notch 15 affords sufficient clearance that the leg 10 is bent over to approximately a 45° angle before this leg touches the web of the muntin 7. This permits it to be set without straining the connection between the leg 11 and the web 14 of the muntin.

Where the window is provided with vertical muntins 5 and 6, each vertical muntin is provided with an opening 19 and a notch 20 at each end, while the horizontal muntin 7 is provided with two pairs of spaced openings 21, the opening 19 being adapted to receive the leg 11 of the clip, the notched portion 20 being adapted to receive the leg 10 of this clip and each set or pair of spaced openings 21 being adapted to receive the projections or prongs 9 of this clip. As will be clearly seen in Figures 2 and 10, the clips which attach adjacent vertical muntins 5 and 6 to the horizontal muntin 7 are reversed, the distance between the pairs of openings 21 being the thickness of the web of the muntins 5 and 6. From the above disclosure and the description in the drawings, it will be apparent that the invention comprehends a novel metal window assembly in which the vertical and/or horizontal muntins are secured to the surrounding sash rails in a more simplified, economical and effective manner than by prior methods and manufacturing practices.

Having thus disclosed the invention, I claim:

1. A metal window comprising encompassing sash rails, intersecting horizontal and vertical muntins for dividing the frame into smaller transparencies and a clip for connecting the end of each muntin to its adjoining sash rail, the sash rails being provided with spaced openings and

the end of the muntin to be joined thereto having a notch and an opening spaced therefrom, each clip having spaced projections extending in opposite directions, the projections extending in one direction being adapted to project through the openings in the sash rail and connect therewith and those extending in the opposite direction projected through the notch and opening in the muntin, and when assembled and bent down upon the muntin, rigidly connecting the muntin to the sash rail.

2. A metal window comprising surrounding sash rails, muntins adapted to be assembled in the window frame to divide it into smaller openings, and clips for assembling the muntins in the frame, the sash rails being provided with spaced openings and the end of the muntin to be attached thereto having a notch and an opening spaced inwardly from the notch, each of the clips comprising a metal member having spaced projecting prongs at one end adapted to be received and anchored in the spaced openings in the sash rail, and a pair of longitudinally spaced legs extending in a direction opposite to the prongs, one of which legs is adapted to be received in the notch disposed in an end of the muntin and the other adapted to be received in the opening spaced inwardly from the notch, the legs when deformed and bent inwardly, rigidly anchoring the muntin in the side rail.

3. A preformed metal window comprising surrounding sash rails provided with a web having laterally spaced openings, intersecting horizontal and vertical muntins having ends adapted to be secured to the web of the sash rails and with these ends provided with openings spaced longitudinally thereof, and metal assembly clips adapted to rigidly connect the ends of the muntins to the sash rails, said assembly clips having oppositely extending projections with the projections extending in one direction being in spaced relation transverse of the clip and adapted to project through the laterally spaced openings and anchored in the web of the sash rail, and the legs extending in the other direction being adapted to be received in the longitudinally spaced openings and anchored onto the muntin to be joined to the sash rail to thereby rigidly connect the muntins to the sash rails.

4. A metal window having intersecting muntins one of which is provided with laterally spaced openings and the other with a notch at its intersecting end and an opening spaced therefrom, and an assembly clip adapted to rigidly connect these muntins and provided with oppositely extending legs, the legs extending in one direction being in spaced relation laterally of the clip and adapted to project through the laterally disposed openings and anchored against a side of the muntin containing these openings, and the legs extending in the opposite direction being disposed in spaced relation longitudinally of the clip and adapted to project through the notch and opening in the other muntin and when deformed against the last mentioned muntin, connecting these muntins in rigid relations.

MILO G. HODSON.
